HORIZONTAL COUNTER FREEZER

Alfred Buttiman, Gardner, Mass., assignor to The Alaska Freezer Co., Inc., Winchendon, Mass., a corporation of Massachusetts

Application July 23, 1937, Serial No. 155,276

5 Claims. (Cl. 259—9)

This invention relates to ice-cream freezers and more particularly to freezers of horizontal type and of relatively small capacity such as are supplied to retail stores and are commonly known as "counter freezers". Such freezers are preferably associated with mechanically cooled ice-cream storage cabinets and utilize the same cooling apparatus for freezing the cream.

It is the general object of my invention to provide an improved freezer of the horizontal counter type, which will be economical to manufacture, simple and convenient in operation, and particularly well adapted to its intended purposes.

To the accomplishment of this general object, important features of my invention relate to the provision of improved means for supporting and driving the parts which agitate the cream; to improved devices for introducing additional material to the freezer while it is in operation and for similarly removing the frozen product therefrom; and to improved devices for effectively closing the freezer but permitting easy removal of the working parts therefrom.

My invention further relates to arrangements and combinations of parts which will be herein-after described and more particularly pointed out in the appended claims.

A preferred form of the invention is shown in the drawings, in which

30 Fig. 1 is a front elevation of my improved freezer;

Fig. 2 is a sectional side elevation, taken along the line 2—2 in Fig. 1;

Fig. 3 is an enlarged sectional side elevation of the rear or driving portion of the freezer;

Fig. 4 is a similar view of the front portion of the freezer;

Fig. 5 is a partial rear view of the front end member, looking in the direction of the arrow 5 in Fig. 4;

Fig. 6 is a partial rear elevation of a spider forming a part of the dash and scraper assembly which rotates within the container, looking in the direction of the arrow 6 in Fig. 3;

45 Fig. 7 is a detail sectional view, taken along the line 7—7 in Fig. 3;

Fig. 8 is a partial sectional plan view, taken along the line 8—8 in Fig. 5;

Fig. 9 is a partial bottom view of the stationary dasher, looking in the direction of the arrow 9 in Fig. 2;

Fig. 10 is a transverse sectional elevation of the dasher, taken along the line 10—10 in Fig. 2;

Fig. 11 is a side elevation of a closing plate for 55 the delivery outlet;

Fig. 12 is a sectional elevation, taken along the line 12—12 in Fig. 11;

Fig. 13 is a detail plan view, partly in section, looking in the direction of the arrow 13 in Fig. 1 and showing clamping means for the front end 5 member;

Fig. 14 is a diagrammatic view showing the circulation of the cooling fluid;

Fig. 15 is a partial side elevation of the rotary dash and scraper assembly;

Fig. 16 is an end view, looking in the direction of the arrow 16 in Fig. 15;

Fig. 17 is a plan view of a dash member, looking in the direction of the arrow 17 in Fig. 15;

Fig. 18 is a side elevation of a bushing to be 15 described; and

Fig. 19 is an end view of said bushing, looking in the direction of the arrow 19 in Fig. 18.

Referring to the drawings, my improved freezer is preferably assembled in a two-part casing, the 20 upper portion 20 of which contains the freezer, while the lower portion 21 houses the motor M by which the dash and scraper assembly is rotated. A door 22 in the front end of the lower portion 21 gives convenient access to the motor. 25

The upper portion 20 comprises an outer casing 24, a cylindrical inner casing 25, front and rear annular frame members 26 and 27, and an inner bearing support 28 which also forms the rear end of the casing 25.

30 A short stud 30 (Fig. 3) is rotatably mounted in the hub portion 31 of the bearing support 28 and is preferably provided with a combined anti-friction and thrust bearing 32. The enlarged inner end portion 33 of the stud 30 extends 35 through the bearing support 28 to the interior of the freezer, and is slabbed off at its inner end portion as indicated at 34. Suitable packing 35 and 36 is provided at the sides of the anti-friction bearing 32. A pivot portion 30^a is formed at the 40 inner end of the stud 30.

A double grooved pulley 37 is fixed to the outer end of the stud 30 and is connected by a pair of V belts 38 to a grooved driving pulley 39 (Fig. 2) on the armature shaft of the motor M. The pulley 37 is preferably dished as indicated in Fig. 3 to bring the belt pull more nearly in the plane of the bearing 32.

45 A cooling coil is provided for the freezer and preferably comprises two sections 40 and 41 50 wound closely on the outer surface of the container casing 25. The space between the coil sections 40 and 41 and the outer casing 24 is filled with suitable heat-insulating material 42.

The cooling coil sections 40 and 41 are prefer- 55

ably connected in parallel, as indicated diagrammatically in Fig. 14, which also shows a by-pass 44 and a thermostat control device 45. The cooling liquid may be furnished from any suitable 5 source but is commonly supplied by the mechanical cooling unit of an ice-cream storage cabinet with which my improved counter freezer is usually associated. The cooling apparatus and associated cabinet are not shown in the drawings 10 of this application.

My improved freezer is provided with a stationary dasher, as 59 (Fig. 2), and with a driven and rotating dash and scraper assembly which comprises spiders 51 and 52 (Fig. 15), cross rods 15 53 and dash bars 54. The back spider 51 is provided with an elongated recess 55 (Figs. 3 and 6) which receives the slabbed inner end portion 34 of the driving stud 30 and with an axial opening 56 to receive the pivot portion 30a of the 20 stud 30.

The front spider 52 (Fig. 16) is provided with a cylindrical opening 57 rotatable on a bushing 58 having a cylindrical outer surface as shown in Fig. 19 and supported in a manner to be 25 described.

Scraper blades 60 are associated with the cross rods 53, and each blade 60 is provided with a plurality of lugs 61 pivotally supported on said rods. The ends of the blades 60 extend through 30 notches 62 (Figs. 6 and 16) in the sides of the end portions of those arms of the spiders 51 and 52 which are connected by the cross rods 53. The notches 62 permit the scraper blades 60 to swing outward to engage the inner surface of the cylindrical casing 25 but prevent excessive inward displacement of the blades. The alternate spider arms 65 (Fig. 15 and 16) are preferably disposed somewhat angularly, as indicated in Fig. 15, with their outer edge portions adjacent the ends of 40 the freezer container and acting as scrapers to prevent accumulation of frozen cream on said ends.

The arms 65 are also provided with inner projections 66 to which are secured the ends of the 45 dash bars 54. These dash bars are each provided with a plurality of angularly disposed outer ribs 67 (Figs. 15 and 17) by which the cream is agitated and is also propelled toward the outer end of the container.

50 The outer end of the container is closed by an end member 70, snugly fitting an annular seat in the outer surface of the front end frame member 26 previously described.

The end member 70 has an inlet or supply passage 71 in its upper portion and an outlet or delivery passage 72 in its lower portion. The inlet passage 71 has a hinged cap 73 to exclude dirt therefrom, and at its lower end merges into a U-shaped opening 75 near the axial center of the 60 end member 70. The opening 75 is of the somewhat unusual outline indicated in Fig. 5, with portions 76 of the opening extending down on each side of the center or bearing portion 77 of the member 70. The utility of this particular 65 form of opening will be hereinafter described.

A stud 80 (Fig. 4) is mounted in an opening 81 in the bearing portion 77 of the end member 70 and has a flange 82 engaging the inner face of said portion 77. A threaded collar 83 is loosely 70 mounted on the outer end portion 84 of the stud 80, and the stud and collar are held in fixed position in the end member 70 by a nut 85.

The inner end of the stud 80 is of tapered hexagonal formation, as indicated at 86, and is designed to receive the bushing 58 which has a cor-

responding hexagonal inner opening 87 (Fig. 19). The bushing 58 is thus supported in axial position but is held from rotation.

The fixed stationary dasher 50 comprises a longitudinally extending shaft 50a having a plurality of recessed wings 90 arranged alternately along opposite sides of the dasher 50 and at an acute angle with its axis, as indicated in Fig. 9. The angle is such that the reaction of the wings 90 assists the movement of the contents of the 10 freezer toward the front or outer end.

The dasher 50 is provided at its rear end with a reduced cylindrical portion 92 which fits loosely in the axial opening 56 of the rear spider 51, which opening 56 also receives the centering stud 15 or pivot portion 30a formed on the inner end of the driving stud 30, as previously described. The stationary dasher 50 is thus fully supported at its rear end in the hub of the rotating spider 51 but is not driven thereby.

The dasher 50 has a hexagonal portion 96 (Fig. 4) loosely fitting within the hexagonal opening 87 (Fig. 19) of the bushing 58. The outer end of the stationary dasher is thus axially supported and held from 20 rotation by the bushing 58, which in turn is 25 mounted on the hexagonal inner end portion 86 of the stud 80 which is secured in the end member 70.

In order to clamp the end member 70 firmly in 30 position to close the freezer, I provide a cross bar 100 (Fig. 1) pivoted at 101 to the end frame member 26. The free end of the cross bar 100 has a cam portion 102 (Fig. 13) adapted to be engaged by a roll 103 mounted in a cam lever 104 35 which is pivoted at 105 to the frame member 26. By swinging the lever 104 in the direction of the arrow a in Fig. 13, the cross bar 100 will be clamped securely in position.

The cross bar 100 is provided with a threaded 40 opening in its middle portion, adapted to receive the threaded collar 83 (Fig. 4). By loosening the nut 85, the collar 83 may be turned to adjust it in the cross bar 100, so that any desired pressure may be exerted on the end member 70. After the desired adjustment is made, the nut 85 is again tightened and a cap 107 (Fig. 4) may be applied to conceal the nut 85, thereby improving the appearance of the freezer as well as preventing tampering with the closure adjustment.

The cover plate 110 for the delivery passage 72 is preferably of the construction shown in Figs. 11 and 12, and is provided with an end slot 111 and a side slot 112. The side walls of the slots are beveled outwardly as indicated in the drawings 55 and are designed to receive spring-pressed studs 114 by which the cover plate is firmly held in position while at the same time it is easily removable for cleaning or other purposes.

Having described the details of construction of 60 my improved freezer, the utility and advantages thereof will be readily apparent. The end member 70 is adjustably mounted on the cross bar 100 and swings easily into and out of position therewith. By the described adjustment, the pressure 65 of the cross bar may be regulated to firmly seat the end member and thus prevent leakage from the container.

When the end member 70 is swung outward, the bushing 58 commonly remains in the spider 70 52 and is removed from the container with the stationary dasher 50 and the rotary dash and scraper assembly. The dasher 50 may then be released from the rotary elements by axially removing the bushing 58 from the spider 52. All 75

of the working parts of the freezer are thus very easily assembled or separated and are driven or held stationary as desired during the operation of the machine.

The particular shape and location of the opening 75, with its lower portions 76, possesses the very important advantage that additional material may be added at any time to the freezer while it is in operation, while at the same time the agitated contents of the freezer will not be thrown outward through the inlet passage 71. It is the tendency of this type of freezer to throw the contents of the freezer outward by centrifugal force and thus create an area of low pressure near the axis, to which additional material is easily fed. The downwardly extended portions 76 of the opening 75 are useful when supplying additional liquid to the freezer, as the liquid can flow inward through the portions 76 while the necessarily displaced air flows upward and outward through the upper part of the opening 75. The provision of an inlet passage of the kind described also allows convenient inspection of the contents of the freezer during the freezer operation without spattering of the contents outward through the inlet opening.

Having thus described my invention and the advantages thereof, I do not wish to be limited to the details herein disclosed, otherwise than as set forth in the claims, but what I claim is:—

1. In a horizontal counter freezer, a casing having a removable front end member, a stud fixed in said end member and having a non-circular inner end portion, a cylindrical removable bushing loosely fitting said stud and having an axial opening of similar non-circular cross section, a dash and scraper assembly supported for rotation at its outer end on said bushing, and a stationary dasher having a non-circular end portion held from rotation by said bushing.

2. In a horizontal counter freezer, a casing having a removable front end member, a stud fixed in said end member and having a non-circular inner end portion, a cylindrical bushing loosely fitting said stud and having an axial opening of similar non-circular cross section, a dash and scraper assembly supported for rotation at its outer end on said bushing, and a stationary dasher having a non-circular end portion held from rotation by said bushing, said bushing being axially removable from said dash and scraper assembly to release said dasher.

3. In a horizontal counter freezer, a container, an end member to close said container, a hinged cross bar having a threaded opening therein, a threaded member mounted on said end member and threaded in said opening in said cross bar, and means to lock said threaded member in angularly adjusted and fixed axial position on said end member.

4. In a horizontal counter freezer, a container, an end member to close said container, a hinged cross bar having a threaded opening therein, a stud in said end member, a collar rotatable on said stud and threaded to fit said opening, and means to lock said collar in angularly adjusted and fixed axial position on said stud and end member.

5. In a horizontal counter freezer, a container, an end member to close said container, a hinged cross bar having a threaded opening therein, a stud in said end member, a collar rotatable on said stud and threaded to fit said opening, means to lock said collar in angularly adjusted position on said stud and end member, and a cap threaded to fit the end of said collar and concealing said locking means.

ALFRED RUTTIMAN. 40
